PIN CLIP

Sidney Golden, Levittown, N.Y., assignor to Avo Uvezian, New York, N.Y.

Filed Mar. 15, 1963, Ser. No. 73,988

Term of patent 3½ years

(Cl. D45—19)

FIG. 1.

FIG. 2.

FIG. 3.

FIG. 1 is a side perspective view of a pin clip showing my new design;

FIG. 2 is a front elevational view thereof; and
FIG. 3 is a top plan view thereof.

The rear or back view of the pin clip is discernible from FIGS. 1 and 3.

I claim:

The ornamental design for a pin clip, substantially as shown and described.
